UNITED STATES PATENT OFFICE

ROBERT D. PIKE, OF PIEDMONT, CALIFORNIA

ROTARY KILN

Application filed May 6, 1926. Serial No. 107,016.

My present invention relates to rotary kilns, particularly those for burning Portland cement clinker, and has for its object to improve both fuel economy and output of a kiln of given dimensions. It has special application as an improvement to the rotary kiln covered in my application for Letters Patent Serial No. 106,103, filed May 3, 1926. As pointed out in the latter application, the ratio of length to diameter has an essential bearing on the fuel economy of rotary kilns. I have found that a kiln 225 feet long with internal diameter of 6 feet has an output of 700 barrels daily and a fuel consumption of 1,020,000 B. t. u. per barrel of clinker weighing 365 pounds per barrel. By my present invention I am able to increase the output to substantially over 800 barrels per day and to reduce the fuel consumption to 800,000 B. t. u. per barrel.

In the aforesaid 225 foot dry process rotary kiln with 6 feet internal diameter when producing 700 barrels per day, the temperature of the gases on leaving the upper end is about 1200° Fahrenheit. One example of the application of my present invention is to expand the diameter of some 30 feet of the upper end of the kiln by 2½ feet, giving an internal diameter of 8.5 feet, and to place inside this expanded zone of the shell a plurality of longitudinally disposed cells formed of corrugated, heat-proof sheet metal. These cells are so disposed that the hot gases pass through each of them at substantially equal velocity, and the feed is about evenly distributed to each at the upper or feed end, and is moved downwardly through each by the rotation of the kiln, until on reaching the lower end of the cells, it drops out of them and back into the kiln, whence it pursues its course downwardly. This arrangement has the effect of greatly enlarging the surface for transmittal of heat to the raw mix in the upper end of the kiln, and results in the reduction of the temperature of the exit gas from 1200° Fahrenheit to about 800° Fahrenheit, and the increase in output and reduction in fuel consumption aforesaid. My reason for expanding the diameter of the portion of the kiln

which houses the longitudinal cells is not only to increase the space available for installing additional surface for heat transmission, but also to reduce greatly the velocity of the gases, thus reducing their tendency to pick up dust. This latter is very important, because the raw mix as it drops out of the lower end of the cells is easily susceptible to being carried along in suspension by the stream of gas, provided the velocity of this gas is great enough. Some dust will be picked up at this point in any event, and my method of returning it to the kiln, as described later, constitutes a novel feature of my invention.

I am well aware that for many years, in wet process kilns, it has been customary to install quadrants in the upper part of the kiln devoted to the evaporation of the water from the slurry. These so-called "quadrants" divide the cross-section of the kiln into four segments and the downcoming slurry into substantially four streams. Whatever benefit may be derived from this arrangement in wet process kilns, I have found it to be totally inadequate to accomplish the object sought by my invention, which primarily is the reduction of the temperature of the exit gases in the dry process example above given from 1200° Fahrenheit to about 800° Fahrenheit. In order to do this I have found it necessary to devise a novel means for providing the necessary area for heat transfer and for other purposes incidental to the main object of the invention.

In the accompanying drawing, I illustrate a typical example of my invention as applied to a kiln for burning Portland cement clinker.

Fig. 1 shows a general partial longitudinal section of the entire equipment;

Fig. 2 shows a central longitudinal sectional view of the section of the kiln adjacent the inlet end;

Fig. 3 shows a cross-section on the line III—III of Fig. 2;

Fig. 4 shows a cross-section on the line IV—IV of Fig. 2.

The kiln comprises a steel plate shell

9

100

having a lining 10 of refractory material. The shell in length is approximately 225 feet, and it is inclined downwardly from the inlet end to the discharge and approximately one-half inch per foot. The section A adjacent the upper or inlet end has an external diameter of 10 feet for about 35 feet. The intermediate section B for about 145 feet has an external diameter of 7 feet; and the section C adjacent the discharge end, for a length of about 45 feet is $7\frac{1}{2}$ feet in external diameter. Section A has a refractory lining 9 inches in thickness; section B has a refractory lining 6 inches in thickness; while section C has a lining 9 inches in thickness. Thus sections B and C internally are of the same internal diameter (i. e., approximately 6 feet).

The lengths specified include suitable taper lengths for rigidly connecting the sections of different diameters, and the usual truncated conical or taper length at the upper end of the kiln. This shell is provided with the usual supporting tires 11 mounted rotatably in the cradles 12 and provided with a girth gear 13 driven by pinion 14 through driving mechanism not shown. The upper end is provided with the usual rotating semi-airtight seal 15. Closure of the lower end of the kiln is effected by the usual firing hood 16, provided with a burner 17. The hot clinkers pass through the usual cooler 18 of rotary or other type, which serves to transfer heat from the clinker to the secondary air for combustion which enters the firing hood through a port 19.

Longitudinal cells 20, 21, and 22 are formed in section A, each about 4 feet long, which when assembled form slipjoints with each other, so as to provide continuous longitudinal cells for the entire length of the assembly. All sections are alike except the uppermost one 20 and lowermost one 22, which have differences to be described later. The intermediate cells 21 are formed of radial, corrugated plates 23, made preferably of a heat-resisting fero-chrome steel, and corrugated, cylindrical sections 24 of the same material. The radial and cylindrical sheets, at their lines of intersection, are securely fastened by riveting or welding. At the center, also suitably secured to the radial plates, is a cylinder or pipe 25, of relatively small diameter. At their outer extremities the radial plates are flanged, so as to provide a mode of fastening to the inside of the steel plate shell of the kiln. This fastening may be effected either by riveting or welding. The aforesaid uppermost section 20 is provided for a portion of its lower length with concentric cylinders 24. These latter are omitted from a short portion of the kiln near the truncated conical feed end, leaving only the radial plates 27 projecting, which,

as the kiln rotates, serve to pick up the feed and distribute it about evenly to each of the several longitudinal cells. The aforesaid lowermost section 22 is provided with an extension 28 of the pipe 25. This is closed at the lowermost end, but is provided with several branch pipes 29, which extend to within a short distance of the inside surface of the kiln.

The described arrangement of radial plates intersecting with cylinders provides a large number of longitudinal cells which offer ample surface for heat transfer to the same number of separate streams of downwardly moving mix. The corrugations of the sheets are provided primarily to allow easy compensation for thermal expansion, but they are also useful in increasing the effective area for heat transfer.

In assembling this structure the uppermost section 20 is placed first and secured to the shell of the kiln. Suitable temporary forms, not shown, are then placed, and the refractory lining rammed home. This latter may be made up of a mixture of Portland cement and diatomaceous earth. The next lower section is then jointed onto the first, so that the longitudinal cells register, secured to the shell and the refractory lining rammed home; and so forth until the entire assembly is placed. Considering the moderate temperature of the gases prevailing at the upper end of the 225 foot rotary kiln, the described structure has a practically indefinite life.

The stack gases carrying dust pass into a chamber 30, and thence through the flue 31 into a dust collector 32. Exhaust fan 33, driven by motor 34, provides the draft and discharges the waste gases through a stack 35. The recovered dust collects in the bottom of the collector and may be removed by any suitable form of dust pump 36, which returns the dust through pipe 37 and delivers it at the lower end of extension 28 for discharge through the pipes 29. This arrangement for returning dust to the kiln prevents its being picked up by the draft a second time, and cuts down the dust circulation. The main feed for the kiln is stored in a feed box 38, and introduced into the kiln in the usual manner through a feed screw 39. If desired, the return dust from the collector 32 can also be fed in through this same feed screw.

It will be understood that the above example of my invention may be varied considerably in detail without departing from the spirit thereof, which involves broadly the application of adequate longitudinal heat-interchanging cells in the upper end of a dry process rotary kiln, in which kiln the ratio of length to diameter is so adjusted that the gases entering the lower end of the cellular passages are at a sufficiently low

temperature so as not to damage the structure of the cells. By means of my invention, fuel economies hitherto considered impossible are attainable in rotary kilns, and a barrel of clinker can be produced for substantially 800,000 B. t. u. and the temperature of the stack gases reduced to about 800° Fahrenheit. Obviously, it would be possible to employ this kiln for wet process; but in such event the invention loses significance, because the fuel consumption in wet process kilns cannot be reduced much, if any, below 1,400,000 B. t. u. per barrel if sufficient heat is to be present in the upper part of the kiln for evaporating the water of the slurry.

When employing reference to the so-called ratio of length to internal diameter, the length referred to is the overall length of the kiln, and the diameter is the principal internal diameter without modification by the upper expanded length. For example, in the case illustrated the ratio is

$$\frac{225}{6} = 37.5.$$

Having thus described my invention, what I claim as new and desire to secure by Letters Patent is:

1. A long, dry-process rotary cement kiln in which the ratio of length to the principal diameter is not less than thirty to one, the diameter of said kiln being enlarged at its upper end to comprise a pre-heating zone, spaced radial and circumferential partitions dividing said enlarged upper end into a plurality of longitudinal passages, said partitions being formed of heat-resistant corrugated metal.

2. An inclined rotary kiln for continuously treating a material having an inlet and an outlet at opposite ends thereof through which the material to be treated is passed, an enlarged section adjacent the inlet end of said kiln provided with radially and circumferentially extending partitions intersecting each other and forming longitudinal passageways therein, said radially and circumferentially extending partitions being formed of corrugated heat resisting metal.

3. An inclined rotary kiln of the character described having a diametrically enlarged section at the upper end thereof divided into a plurality of longitudinally extending open-ended passageways, said passageways being outlined by radially and circumferentially extending partitions of corrugated metal having a high heat conductivity and a high degree of heat resistance.

ROBERT D. PIKE.
